(57) **CLAIM**

The ornamental design for a frame for a high-performance balance bicycle, as shown and described.

DESCRIPTION

FIG. 1 is a perspective view of a frame for a high-performance balance bicycle.

FIG. 2 is a first side view thereof;

FIG. 3 is a second side view thereof;

FIG. 4 is a bottom view thereof;

FIG. 5 is a top view thereof;

FIG. 6 is a rear view thereof;

FIG. 7 is a front view thereof; and,

FIG. 8 is a perspective view thereof shown in an exemplary environment.

The broken lines are included for the purpose of illustrating the environment structure and form no part of the claimed design.
